UNITED STATES PATENT OFFICE.

ERNEST E. EAST, OF LOS ANGELES, CALIFORNIA, ASSIGNOR TO AUTOMOBILE CLUB OF SOUTHERN CALIFORNIA, OF LOS ANGELES, CALIFORNIA, A CORPORATION OF CALIFORNIA.

DESIGN FOR A TRAFFIC-SIGNAL CASING.

Application filed February 11, 1924. Serial No. 8,608. Term of patent 14 years.

To all whom it may concern:

Be it known that I, ERNEST E. EAST, a citizen of the United States, residing at Los Angeles, in the county of Los Angeles, State of California, have invented a new, original, and ornamental Design for a Traffic-Signal Casing, of which the following is a specification, reference being had to the accompanying drawing, forming a part thereof.

Figure 1 is an elevation of the traffic signal casing, showing my new design.

Figure 2 is a top, plan view of the traffic signal casing.

I claim:

The ornamental design for a traffic signal casing, as shown.

ERNEST E. EAST.
